UNITED STATES PATENT OFFICE

GLADWIN E. JOHNSON, OF CHICAGO, ILLINOIS

GAME APPARATUS

Application filed November 7, 1931. Serial No. 573,555.

This invention relates to game apparatus, and in its present embodiment is designed for a coin-operated amusement machine used for playing a card game. The invention may be embodied in apparatus for playing any game in which a movable indicator or plurality of movable indicators are used.

The indicators are slidably mounted on upright members, and are adapted to be propelled upwardly by manual actuation of a plurality of levers. The main object of the invention is to provide means for retaining the actuated indicators against downward movement until the operator desires to release the same. Novel forms of mechanism for holding and for releasing the indicators are part of the present invention.

In that embodiment of the invention shown in the drawings, playing cards are reproduced on the face of a support along the paths of the indicators, for designating the value of the play when the indicators come to rest.

In the drawings—

Fig. 1 is a front elevation of a game apparatus embodying my invention.

Fig. 2 is a transverse vertical sectional view taken on the line 2—2 of Fig. 1.

Fig. 3 is a transverse vertical sectional view of a modified form of apparatus.

Fig. 4 is an enlarged section of a detail of construction.

Fig. 5 is a horizontal sectional view taken on the line 5—5 of Fig. 4.

Fig. 6 is an enlarged detail taken on the line 6—6 of Fig. 2.

In the present embodiment, a base 10 supports a casing 11, which comprises rectangularly shaped walls forming a boxlike structure, and forwardly of the casing is a glass wall 12. The casing has reproduced on its front wall 13 a plurality of playing cards arranged in five vertical rows and eight horizontal rows. Value indicating numerals are arranged in another vertical row at one side of the wall 13. The top 14 of the casing carries a depending cross bar 15 which is connected by a horizontal cross piece 16 to the wall 13.

Referring now to Figs. 1, 2, 4, 5 and 6, a

plurality of rotatable rods 17 are mounted in the base 10 and cross piece 16. The rods 17 are normally held against rotation by a coiled spring (not shown), connected to the rod and to the casing, or by any other suitable means. Each rod 17 is grooved longitudinally as shown at 18, and an indicator 19 is slidably mounted on each of said rods. The indicator 19 is bored longitudinally and provided with an interiorly projecting pin 20 which engages the groove 18 and prevents rotation of the indicator 19 relatively to the rod 17. The indicator 19 is also provided, exteriorly, with a spring pawl 21 adapted for engagement with a series of longitudinally disposed ratchet teeth 22 located on the wall 13 between the vertical rows of playing cards.

A propelling lever 23 is fulcrumed on an upright support 24 which rises from the base 10, preferably in the same vertical plane as the glass wall 12 for which it forms a mounting support. One propelling lever is provided for each indicator 19. The lever 23 has a forked end 25 which loosely straddles the rod 17 below the indicator 19. Normally the weight of the indicator holds the outer end of the lever 23 in elevated position. Rubber pads 26 and 27 separate the lever ends from the base 10.

To play the game, the player manually actuates the levers 23, striking the same sharply and thereby propelling the indicators 19 upwardly, the extent of travel being determined by the force of the impact on the outer ends of the levers. The pawl 21 of the indicator 19 engages one of the teeth 22 on the wall 13, that is, the uppermost tooth which the indicator has passed in its travel upwardly, and thus the indicator is held against return movement, as shown in Fig. 2. The indicator 19 will designate a particular playing card, namely, the one to the left of the indicator, as viewed from the front of the apparatus, and when the five indicators have been actuated as intended, and the score noted, the rods 17 may be rotated by actuating the crank arm 28 or by any other suitable means, which may be manually operated and coin controlled or automatically operated. In the present embodiment the

arm 28 is operatively connected to a plunger 29. A coin slot is indicated at 30. The operative connections between the arm 28 and the parts 29 and 30 form no part of the present invention.

5 The rotation of the rods 17, carrying the non-rotatable indicator 19, results in turning the indicator with the rod so as to move the pawl 21 out of engagement with the teeth 22, whereupon the indicator falls by gravity to the base 10, carrying the lever 23 from its dotted line position in Fig. 2, to the solid line position. The rod 17 is automatically returned to the normal position after it has 10 been rotated.

15 Instead of making the rod 17 rotatable, as explained, the disengagement of the pawl 21 from the teeth 22 may readily be effected by temporarily moving the rod 17 away from the teeth 22, that is, by reciprocating the rod 17 instead of rotating it.

20 Referring now to the modified construction shown in Fig. 3, it will be seen that the teeth 22 heretofore described have been removed from the wall 13. In lieu thereof 25 projections or pawls 31 are fixed to a rod 32 and the indicator 19 is mounted on a non-rotatable rod 33. In this construction the engagement of the indicator 19 with a pawl 30 31 holds the indicator in its indicating position, and the actuation of the rod 32 results in disengagement of the parts. As shown in Fig. 3, the rod 32 is movably mounted in slots in the upper and lower supports 16, 10, 35 so that the rod may be moved away from the rod 33. The rod 32 is automatically returned to normal position by a coiled spring (not shown) connected to the rod and to the casing, as is well understood. Obviously the 40 rod 32 might be made rotatable to move the pawls 31 out of engagement with the indicator 19, for releasing the indicator.

45 Changes may be made in details of construction without departing from the scope of my invention and I do not intend to be limited to the exact form shown and described, except as set forth in the appended claims.

I claim:

50 1. Game apparatus including an upright member provided with a longitudinally extending row of toothed projections, a rod parallel with said toothed member and mounted in juxtaposition to the same, an indicator slidably on said rod, a pawl on the indicator adapted to engage the toothed member to hold the indicator against downward movement, means for propelling the indicator upwardly on the rod, and means for 55 rotating the rod to move the pawl on the indicator out of engagement with the toothed member for releasing the indicator.

55 2. Game apparatus including a vertical member provided with a longitudinally extending row of toothed projections, a longi-

tudinally grooved rod parallel with the toothed member and rotatably mounted in juxtaposition to the same, an indicator slidably mounted on said grooved rod, an internally projecting pin on the indicator in engagement with the grooved rod, a pawl on the indicator for engaging the toothed member to hold the indicator against downward movement, means for propelling the indicator upwardly on the grooved rod, and means for rotating the grooved rod to move the pawl on the indicator out of engagement with the tooth projections on the support and to release the indicator.

3. Game apparatus including a casing, the exposed surface of one of the upright walls of the casing carrying reproductions of playing cards arranged in rows, top and bottom walls extending forwardly beyond said upright wall, a plurality of rotatable rods mounted in said top and bottom walls in juxtaposition to the upright wall, an indicator slidably mounted on each rod, means for propelling the indicators upwardly on said rods, means between the rods and the upright wall for engaging the indicators, and means for releasing said engaging means.

4. Game apparatus including a casing, the exposed surface of one of the upright walls of the casing carrying reproductions of playing cards arranged in rows, top and bottom walls extending forwardly beyond said upright wall, a plurality of rods mounted in said top and bottom walls in juxtaposition to the upright wall, an indicator slidably mounted on each rod, means for propelling the indicators upwardly on said rods, a series of toothed projections on said upright wall between the rows of playing card reproductions, a pawl on the indicator for engaging said toothed projections, and means for actuating the rod to release the pawl from said projections.

5. Game apparatus including a casing, the exposed surface of one of the upright walls of the casing carrying reproductions of playing cards arranged in rows, top and bottom walls extending forwardly beyond said upright wall, a plurality of rods mounted in said top and bottom walls in juxtaposition to the upright wall, an indicator slidably mounted on each rod, means for propelling the indicators upwardly on said rods, means between the rods and the upright wall for engaging the indicator, and means for releasing said engaging means, said means for propelling each indicator consisting of an upright support, a lever fulcrumed on the support, one end of the lever being forked and straddling the rod, and cushioning means between the lever ends and the base of the casing.

6. Game apparatus including an upright member provided with a longitudinally extending row of toothed projections, a rod par-

allel with said toothed member and mounted in juxtaposition to the same, an indicator slideable on said rod, a pawl on the indicator adapted to engage the toothed member to hold the indicator against downward movement, means for propelling the indicator upwardly on the rod, and means for actuating the rod to move the pawl on the indicator out of engagement with the toothed member for releasing the indicator, said means for propelling the indicator consisting of an upright support adjacent the rod, a lever fulcrumed on the support, one end of the lever being adapted to contact with the under side of the indicator, and cushioning means beneath the lever ends.

In testimony that I claim the foregoing as my invention, I affix my signature this 3rd day of November, 1931.
